UNITED STATES PATENT OFFICE.

CATHOLINA LAMBERT, OF NEW YORK, N. Y.

DESIGN FOR A HANDKERCHIEF.

SPECIFICATION forming part of Design No. 16,316, dated October 6, 1885.

Application filed September 2, 1885. Serial No. 176,036. Term of patent 3½ years.

To all whom it may concern:

Be it known that I, CATHOLINA LAMBERT, of the city, county, and State of New York, have invented a new and original Design for 5 a Handkerchief, of which the following is a specification.

Reference is to be had to the accompanying drawing, forming a part of this specification, in which the figure is a plan view of my newly-10 designed handkerchief.

The leading feature of my design consists of a lawn-tennis outfit of rackets, balls, and net shown upon the handkerchief.

A represents a rectangular or square border 15 of a handkerchief. Within this border is shown the lawn-tennis net *a*, rackets *b b*, and tennis-balls *c c*. The net *a* is represented as being attached to posts *d d*, which are represented as being braced by guy-ropes *e e*, attached to the posts and to pins *f f*. The rack-20

ets *b b* are represented with crossed handles, and occupying a position above the net *a*. The balls *c c* are shown in the side angles formed by the crossed rackets *b b*, so the whole together represents an entire lawn-tennis 25 outfit.

I claim—

1. The design for a handkerchief herein shown and described, the same consisting of a representation of a lawn-tennis outfit consisting of a stretched net, rackets, and balls.

2. The design for a handkerchief herein shown and described, the same consisting of the representation of the stretched net *a*, crossed rackets *b b* above the net, and balls *c c* at the side angles of the rackets.

CATHOLINA LAMBERT.
